UNITED STATES PATENT OFFICE.

FRANK A. ROSS, OF CHICAGO, ILLINOIS, ASSIGNOR TO STEWART-WARNER SPEEDOMETER CORPORATION, OF CHICAGO, ILLINOIS, A CORPORATION OF VIRGINIA.

DESIGN FOR A VEHICLE LAMP.

Application filed March 10, 1922. Serial No. 1,103. Term of patent 14 years.

To all whom it may concern:

Be it known that I, FRANK A. Ross, a citizen of the United States, residing in the city of Chicago, in the county of Cook and State of Illinois, and having post-office address at 1828 Diversey Parkway, Chicago, Illinois, have invented a new, original, and ornamental Design for a Vehicle Lamp, of which the following is a specification, reference being had to the accompanying drawings, forming a part thereof.

In the drawings:

Figure 1 is a front elevation of a vehicle lamp embodying my new design.

Figure 2 is a side elevation of the same.

Figure 3 is a top plan view.

I claim:

The ornamental design for a vehicle lamp substantially as shown.

In testimony whereof, I have hereunto set my hand at Chicago, Illinois, this 7th day of March, 1922.

FRANK A. ROSS.
